TOY LOG TRAILER

Gary B. Smart, 3500 Carter Road,
Portsmouth, Va. 23703

Filed Oct. 31, 1972, Ser. No. 302,408

Term of patent 14 years

Int. Cl. D21—01

U.S. Cl. D34—15 AJ

FIG. 1

FIG. 4

FIG. 3

FIG. 1 is a top plan view of a toy log trailer showing my new design;

FIG. 2 is a front elevational view thereof;

FIG. 3 is a right side elevational view thereof, the left side being a mirror image thereto;

FIG. 4 is a bottom plan view thereof on a reduced scale.

I claim:

The ornamental design for a toy log trailer, as shown and described.
